UNITED STATES PATENT OFFICE.

HERMAN C. KOEHLER, OF MILWAUKEE, WISCONSIN.

BROOM-PROTECTOR.

1,287,047.

Specification of Letters Patent. Patented Dec. 10, 1918.

Application filed March 30, 1917. Serial No. 158,506.

To all whom it may concern:

Be it known that I, HERMAN C. KOEHLER, a citizen of the United States, and resident of Milwaukee, in the county of Milwaukee and 5 State of Wisconsin, have invented certain new and useful Improvements in Broom-Protectors; and I do hereby declare that the following is a full, clear, and exact description thereof.

10 My invention relates to improvements in attachments for brooms, one object being to provide simple and efficient means for protecting the head of an ordinary broom.

It is a matter of common knowledge that 15 the straws which compose the heads of ordinary brooms frequently become broken or otherwise damaged when said brooms are in use. This is especially true when the edge of the broom strikes an obstacle, some of the 20 straws being frequently held by the latter and broken off when the broom is moved away from the same. One reason for this damage to the straws lies in the fact that inadequate means is usually provided for retaining them within certain limits.

25 My invention is adapted to confine the straws of any ordinary broom head to prevent their injury.

An additional object is to provide an attachment for broom heads by which the 30 stiffness of the broom may be varied.

A still further object is to provide means whereby a dust cloth may be secured to the usual broom head.

35 With the foregoing objects and advantages in view the invention resides in the novel features of construction which will be hereinafter more particularly pointed out and claimed.

40 In the accompanying drawing:

Figure 1 represents a perspective view of a protector constructed in accordance with 45 my invention;

Fig. 2 is a side elevation of a broom head having my invention applied; and

Fig. 3 is a similar view showing the manner in which a dust cloth may be held to the broom head by the invention.

In the preferred embodiment of my device 50 as shown in the drawing, wherein similar reference characters denote like parts, it will be noted that the same consists broadly of a pair of clamping frames adapted to be disposed one on each side of a head H of a broom B, the several parts of the frames

serving to readily confine the straws S which compose the head.

More specifically the device consists of a pair of end members 1, each formed of spring wire bent upon itself as at 2. Each 60 of the end members 1 thus is composed of a pair of arms 3 which, if permitted to do so, would be moved to a substantially parallel relation as a result of the spring tension exerted by the bend 2.

65 However, the arms 3 of each member are crossed intermediate their ends as at 4, and the free ends of the corresponding arms of each member are connected by cross-bars 5 also formed of wires of an appropriate 70 diameter. This construction in effect produces a pair of substantially U-shaped members, each of which consists of a pair of arms 3 and a cross-bar 5, the adjacent arms being connected at 2. All of these members are 75 preferably formed from a single spring metal wire bent into the desired shapes, the opposite ends of the wire being brought together and loosely connected, they being provided with eyes 6 which are disposed one 80 within the other to hold the said ends together. The arms 3 of one U-shaped member are both disposed inwardly of the arms of the other U-shaped member, one of the inner arms being the arm on which one eye 6 85 is formed, whereby said inner arms may be moved toward each other slightly owing to the loose connection of said eyes.

80 Each of the arms 3 has its portion adjacent the bend 2 bent inwardly toward the corresponding arm of the other member whereby to form ears 7. Each of these portions is preferably constructed by bending each arm inwardly toward the other corresponding arm at right-angles as shown at 8 95 and then continuing it downwardly as at 9 until it merges into the bend 2. The ears 7 thus formed on each end member are preferably spaced apart a distance substantially equal the thickness of the broom head and are 100 adapted to receive said broom head therebetween as clearly shown in Figs. 2 and 3.

105 The cross-bars 5 are a length substantially equal the width of the broom head, but the portions of the device adjacent the bend 2 may be moved inwardly or outwardly with respect to each other so that the broom head may be gripped more or less tightly. To move these parts of the end members toward each other a helical contracting spring 110

10 is provided, the opposite ends having eyes
11 to be disposed in a pair of corresponding
ears 7.

In applying the protector to a broom head,
5 the cross-bars 5 are forced apart a sufficient
distance to permit the head H to move there-
between, said cross-bars being spaced a suit-
able distance from the free ends of the
straws S, while the ears 7 are disposed on
10 the opposite sides of the broom head adjac-
ent its connection with its handle. From
the figures of the drawing it will be noted
that the cross-bar of one of the U-shaped
members above mentioned is disposed on one
15 side of the broom head, and the ears of said
member are located in engagement with the
other side of the head so that the arms of
such member extend diagonally across the
edges of the broom. As the result of the
20 loose connection formed by the eyes 6 and
the engagement of the spring 10 with the
ears 7 of the inner arms 3, it will be seen
that said inner arms 3 will be moved toward
each other throughout their length. Thus
25 the broom head will be gripped at spaced
points on opposite sides, that is to say the
outer portion of the head on one side will be
gripped by the outer ends of the inner arms
3, while the other side of the head adjacent
30 its inner end will be gripped by the portions
of the inner arms 3 adjacent the ears 7.

By placing the cross-bars 5 adjacent the
free end of the straws S it will be obvious
35 that a broom head of considerable stiffness
will have been produced, but on the other
hand if such bars are spaced a considerable
distance from the ends of the straws the
head will be much more flexible. These
40 cross-bars are further used for retaining a
dust cloth C upon the end of the head H,
said cloth being wrapped about the head in

any preferred manner so that the bars may
grip the same as in Fig. 3. It is evident that
an extremely simply constructed combination
protector and dust cloth holder has been 45
produced which will effectively confine the
straws of a broom head to prevent their be-
coming broken off or otherwise injured and
thus prolonging the life of a broom.

I claim:

A device of the class described comprising
a pair of end members formed of spring
wire bent upon itself, the arms of each mem-
ber being crossed under tension, the inner
arm of one member having an eye formed 55
at its free end, a connecting wire united
with the free end of the inner arm of the
other end member and having an eye on
its free end loosely connected with the first
mentioned eye whereby said inner arms may 60
move inwardly toward each other slightly, a
second connecting wire united with the free
ends of the outer arms of the end members,
each of the arms of one end member adjac-
ent the bend thereof being bent inwardly 65
toward its corresponding arm of the other
end member to provide V-shaped ears, the
same forming spring receiving seats, the
ears of each end member being adapted to
70 straddle one edge of the broom, said con-
necting wires also being disposed on oppo-
site sides of the broom, and a contracting
coil spring having its opposite ends con-
nected with the ears formed in said inner 75
arms whereby to draw the said arms to-
gether throughout their length to evenly
confine the broom.

In testimony that I claim the foregoing I
have hereunto set my hand at Milwaukee,
in the county of Milwaukee and State of 80
Wisconsin.

HERMAN C. KOEHLER.
